OIL WELL BAILER AND CLEANER

Paul Cavins, Long Beach, Calif.

Application June 23, 1937, Serial No. 150,003

12 Claims. (Cl. 166—19)

The present invention relates to oil well bailers and cleaners of a type adapted to be lowered into a well to take charge of liquid and solid matter therefrom, and to remove the charge from the well. The invention includes methods of cleaning as well as apparatus therefor.

A principal object of the invention is to provide a cleaner of the above type which will clean the perforations in perforated well pipe at the bottom of the well, or at any desired point above the same. The cleaner disclosed herein may be operated successively at various depths in the well to clean the openings throughout the entire perforated area of the well pipe.

15 A principal object of the invention is to provide such a cleaner having a closed, substantially air-tight suction chamber and a valve controlling the inlet to the same, with means for positively opening the valve to draw a charge from the well by movement of the cleaner in the well.

20 A further object of the invention is to provide a cleaner of the above type equipped with a valve which may be operated to effect the drawing of a charge into the tool from the well, with automatically operable means for retaining the valve displaced from its seat during the time that the cleaner is being removed from the well, the valve operating means being constructed and arranged for reapplication of the valve to its seat to seal the suction chamber, thus eliminating the necessity for entirely replacing the valve, as has been done in the prior art when frangible valve closures and the like have been used.

25 A further object of the invention is to provide a cleaner which may be conveniently assembled by adding units of equipment to bailers of a well known type of the prior art.

30 Another object of the invention is to provide a cleaner adapted to clear the perforations in a well pipe in selected confined areas.

35 The cleaner of the present invention may be operated to wash the perforations in the well pipe either by an outward or an inward rush of fluid through said perforations.

40 The invention may be considered as an improvement of the bailer disclosed in the Reissue Patent No. 19,679 of Omar A. Cavins, August 27, 1935, the improvement residing in the addition of standard units of equipment to the above mentioned bailer in order to better adapt it for the cleaning of perforations in well pipe, at any desired depth in the well. The aforementioned patent comprises a closed substantially air-tight suction chamber with a valve closing the lower end of the same, which valve is automatically

5 opened when the bailer is arrested in its descent in the well. Disposed below the suction chamber of this bailer is a one-way flapper valve to retain the charge drawn into the device by suction, and below this valve is a shoe including a bottom inlet, through which the charge is drawn when the suction chamber valve is opened. Arranged above the suction chamber of this bailer, is a jar unit through which the tool is suspended on the lowering line, and which unit may be used 10 in jarring the bailer loose if it becomes stuck in the hole.

15 While the bailer of the above mentioned patent is well adapted for the cleaning of perforations in well pipe at any selected depth in the well, its operation is most effective in the withdrawing of heavy charges of mud, fish and the like from the bottom of the well, although improvements in the nature of adjustable side inlet ports into the shoe of this bailer, as shown in 20 my Patent No. 2,088,151, have adapted this bailer for efficient cleaning operations including perforation washing at positions above the bottom of the well.

25 The present invention may be considered as an improvement on the bailer of the above mentioned patent to Omar A. Cavins, by adding thereto what is hereinafter termed an "up-trip unit" and a "pack-off shoe unit", these attachments serving to equip the bailer for more effective 30 operation in connection with perforation washing.

35 The up-trip unit comprises a plurality of wall engaging elements in the nature of bowed springs which retain the main valve stem of the valve which controls flow of fluid to the suction chamber against upward movement when the bailer is lowered to cleaning position and then elevated, thereby positively moving the valve from its seat to cause a rush of fluid into the suction chamber 40 to take a charge from the well.

45 The pack-off shoe unit is a replacement of the regular shoe of the bailer of the above mentioned patent to Omar A. Cavins, and includes a pair of spaced packers with inlet ports between the same, which packers confine the suction resulting from the opening of the main valve so that the perforation cleaning may be limited to and made more intense in a selected area of the wall of the perforated well pipe. The pack-off 50 shoe unit also includes a fluid by-pass traversing the spaced packers to facilitate lowering of the tool into the well.

55 The cleaner generally equipped as described above is lowered into the well until the spaced

packers of the pack-off shoe are at the desired depth for perforation cleaning, and the cleaner is then moved upwardly under influence of its suspension line, and the engagement of the wall drag elements of the up-trip unit positively forces the suction chamber valve from its seat, the suction resulting from the taking of a charge following the opening of the valve serving to clean the perforations in the well pipe between the packers of the pack-off shoe assembly. After the charge has been taken, the tool is elevated from the well, the charge being retained by the well-known flapper valve mentioned above, and at the surface of the well the charge may be removed as hereinafter described. When one area of the perforations has thus been cleaned, the main valve may be manually re-set to its seat, after which the tool may be again lowered into the well to withdraw a succeeding charge, cleaning another area of perforations in the well pipe either above or below the perforations previously cleaned.

In the drawings, which are illustrative of a preferred form of the invention, which drawings are in no sense restrictive—

Figure 1 is a sectional view of a well, showing one form of the cleaner in position therein.

Figure 2 is an enlarged vertical sectional view of the upper portion or jar unit of the cleaner, showing the same in position in the well.

Figure 3 is a similar view of the up-trip unit which connects with the lower end of the jar unit shown in Figure 2.

Figure 4 is a similar view of the suction chamber of the cleaner, which connects with the lower end of the portion of the tool shown in Figure 3.

Figure 5 is a similar view of the portion of the cleaner including the charge retaining flapper valve, and discharge port above the same, which connects with the lower end of that portion of the tool shown in Figure 4.

Figure 6 is a similar view of the lower end of the cleaner including the pack-off shoe unit, which is connected with the lower end of that part of the tool shown in Figure 5.

Figure 7 is a view similar to Figure 3, but showing the arrangement of the parts when the main valve has been forced from its seat.

Figure 8 is a view similar to Figure 4, but showing the main valve off of its seat.

Figure 9 is an enlarged horizontal sectional view of the tool, taken along the line 9—9 of Figure 3.

Figure 10 is a similar horizontal sectional view of the tool taken along the line 10—10 of Figure 6.

Figure 11 is a similar horizontal sectional view of the tool taken along the line 11—11 of Figure 8.

Referring to Figure 1, the tool comprises a jar unit A, an up-trip unit B, a suction chamber and valve assembly C and a pack-off shoe unit D. In the above mentioned patent to Omar A. Cavins, a tool is shown which was primarily used for bailing, consisting of only the parts A and C with a special shoe having a central bottom inlet attached to the lower end of the assembly C in place of the pack-off unit D. In practice, the parts of the up-trip and the pack-off shoe units B and D are so standardized that they may be fitted into the bailer of the type shown in the said Omar A. Cavins patent by disconnecting the jar unit A and suction chamber unit C of the tool of that patent, inserting therebetween the up-trip unit B of the present cleaner, and by

replacing the shoe of the Omar A. Cavins bailer with the pack-off shoe unit D of the present cleaner in the manner shown in Figure 1.

The jar unit, as shown in Figure 2, comprises an upper casing section 10 which is threaded to a connecting collar 12, said collar being threaded and welded as shown to the upper end of a lower section of casing 14. The collar 12 has a central opening 16 therethrough in order to slidably receive a rod 18, said rod having fixed thereto a head 20 which is adapted to engage the lower face of the collar 12 as an anvil, in order to jar the tool loose if it becomes stuck in the well.

The upper end of the rod 18 is threaded into a solid connector 22 which is in turn secured to a suspending eye member 24 by means of a tool joint 26, the suspending eye being adapted to receive the well known sand line for lowering the tool into the well. The lower end of the casing section 14 is threaded to the upper end of a latching block housing 26 which may house if desired a latching block 28 for use only when the tool is assembled in the manner of a bailer shown in the above mentioned Omar A. Gavins patent, although this latching block may be omitted when the tool is assembled as a cleaner, if desired.

Referring to Figure 3, the housing 26 is threaded at its lower end by means of a tool joint to a connecting sub 30 which forms the top member of the "up-trip" unit. To the lower end of sub 30 is secured the up-trip unit sleeve 32, the latter being threaded at its lower end to a housing 34 which contains a slidably latching block 36 for use with the cleaner, identical with the block 28 of the jar unit.

Disposed within the up-trip unit sleeve 32 and between the lower end of the sub 30 and the upper end of the latching block 36 is a valve-operating rod 38, and slidably mounted on said rod near its upper end is a spring retaining collar 40. The rod 38 is supported within the sleeve 32 by a collar 41 secured within said sleeve. Secured to the collar 40 at their upper ends in any suitable fashion are wall engaging elements 42. These elements may be of any desired type, and they extend outwardly beyond the up-trip unit sleeve through the slots 44 in said sleeve. The valve operating rod 38 has secured thereto a fixed upper collar 46 which limits the downward movement of the spring retaining collar 40 in a manner hereinafter described, and a spring expanding knob 48 at a point spaced below the collar 46. The wall engaging elements 42 are in the form of bowed spring members as shown, and they extend outwardly from their retaining collar 40 and engage the wall of the well casing intermediate their ends, and at their lower ends said springs are bent inwardly to lie against the rod 38 as shown at 50. The extreme lower ends 52 of the springs 42 may be bent outwardly for effective engagement with the spring expanding knob 48.

The latching block 36 normally rests within the opening in its housing sub 34 supported on the upper face of the main valve stem 54. This block is equipped with a stop bolt 56 extending into a suitable slot 57 in the wall of the housing 34 to limit the downward movement of said block, and is also equipped with a spring-pressed latch 58 normally housed within a cavity 60 in the block, but adapted to be forced outwardly by its spring into a slot 62 in the wall of the housing 34, when the block is moved downwardly as hereinafter described, in order to lock the valve stem 54 in its 75

lower position with the main valve off of its seat.

When the cleaner is being lowered into the well, the up-trip unit is in the condition shown in Figure 3, and the springs 42 will move along in frictional engagement with the wall of the well casing, the spring retaining collar being at the upper end of the valve operating rod 38. When the desired area for cleaning of the well has been reached, the descent of the cleaner is stopped, and then it is lifted upwardly. During this upward movement, the wall engaging elements 42 will be held in relatively fixed position by their frictional engagement with the wall of the well casing, and the entire cleaner including the valve operating rod 38 will move upwardly with respect to the springs until the ends 52 of the springs engage the expanding knob 48. At this time, the increased frictional engagement of the springs with the well casing wall caused by the expansion of the springs effected by the collar 48, will be sufficient to maintain the valve operating rod 38 against further upward movement. Continued upward movement of the cleaner will cause a downward force against the latching block 36, which will in turn be imparted to the upper end of the valve stem 54, and this force will be sufficient to move the main valve from its seat against the tension of its spring as hereinafter described. The movement necessary to completely withdraw the main valve from its seat will be sufficient to lower the latching block 36 and move the bolt 58 below the upper end of the slot 62, at which time said bolt will move outwardly under pressure of its spring to latch the block in its lower position as shown in Figure 7, thus retaining the main valve off of its seat. Further upward movement of the cleaner will cause the lower ends 52 of the springs 42 to ride over the expanding collar 48, as shown in Figure 7, thus decreasing the frictional engagement of the springs with the wall of the well casing, to permit the cleaner to be withdrawn from the well after a charge has been taken into the tool.

Referring to Figure 4, the lower end of the housing 34 is shown secured to the upper end of a housing 64 which defines the upper end of a closed, substantially air-tight suction chamber 65. This housing is provided with a bore 66 through which the valve stem 54 passes, and suitable packing 68 is positioned in the upper end of said bore surrounding the valve stem, which packing is maintained to seal the upper end of said chamber around the valve stem by means of a gland 70 threaded into the upper end of said bore. Below the packing, the valve stem has formed integral therewith a collar 72 provided to guide said stem in the bore.

The lower end of the housing 64 is threaded to the upper end of a relatively long sleeve 74, which forms the wall of the suction chamber, and at its lower end, said sleeve is threaded to a main valve body 76 which in turn is secured by means of a tool joint to the sub 78, the latter being threaded at its lower end to the upper end of a sleeve 80. The sub 78 has a bore 82 therein, and at the upper end of said bore a valve seat member 84 is threaded into a counterbore 86 in the lower end of the valve body 76.

The valve body 76 is formed with an upwardly and outwardly tapered bore 88, forming with bore 82 and valve seat 84 an inlet fluid way between the lower chamber 90 and the suction chamber 65.

The closure for sealing the inlet to the suction chamber 65 is shown in the form of a valve mem-

ber 92, the same being threaded or secured in any suitable manner to the lower end of the valve stem 54, the valve member being fixed to an extension of the valve stem which passes through the valve seat, and thus the valve member comes upon its seat from below, so that pressure of the well fluid when the cleaner is being lowered into the well will tend to close the valve, or force it into more intimate engagement with its seat. A lock nut 93 may be provided to lock the valve member on the lower end of the rod 54.

Within the suction chamber sleeve 74, and threaded to the interior of the housing 64, is a spring housing sleeve 94, which sleeve has threaded within its lower end a collar 96. This collar serves as a bearing and guide for a sleeve 98 welded to the valve stem 54. The valve stem 54 is reduced in diameter below its collar 72.

Welded to the reduced portion of the valve stem is a fixed collar 100, said collar having a reduced lower portion forming a downwardly facing shoulder 101 and loosely mounted on the reduced portion of the collar is a second collar 103. Between the lower end of said collar 103 and the upper end of the collar 96 is a main spring 102 which tends to urge the main valve to its seat.

Any suitable means may be provided to adjust the tension of the spring 102, for instance, by rotation of the valve stem 54 to adjust the force by which the valve member engages its seat, particularly for decreasing the effect of the spring when the tool is changed from a bailer of the type shown in the Omar A. Cavins patent, to a cleaner as shown in the present invention.

The collar 96 is adapted for vertical movement in the sleeve 94 when rotated therein, having a hexagonal opening as shown in Fig. 11 which fits the hexagonal sleeve 98 on the valve stem. By turning the upper end of the valve stem 54 with a wrench, when the tool units above said end are removed, sleeve 98 will impart turning movement to the collar 96, moving it toward or from the fixed collar 100, thus regulating the force of the spring 102. By removing lock nut 93 and valve member 92 from valve operating rod 54, said rod with its collars 98 and 100 may be removed from the barrel as a unit, after stuffing box nut 70 is removed, the collar 72 carrying packing 68 with it during removal.

Within the bore of the housing 64 and at the upper end of the suction chamber is a suitable relief valve 104, which is adapted to relieve excessive pressure from the suction chamber when the cleaner is being elevated from the well, which is well understood in the art.

Referring particularly to Figure 5, the lower end of the sleeve 80 is threaded to a connecting sleeve 106, having a lower inner sleeve extension 108 which extends down into an outer discharge valve sleeve 112. Attached to the lower end of the sleeve extension 108 is a collar 114 which forms a fluid way controlled by the charge retaining flapper valve 116. The sleeve extension 108 is provided with a suitable outlet port 118 similar to the port 33 of Figure 1 of the above mentioned Omar A. Cavins patent, which port may be aligned with a cooperating outlet port 120 in the sleeve 112, the latter corresponding with the port 34 in Figure 1 of the above mentioned patent to Omar Cavins, when it is desired to discharge the bailer. The alignment of these ports may be effected at the surface of the well when the cleaner is withdrawn there-

from, in a manner well known in the art, by rotating the sleeve 112 with respect to the inner sleeve 108, to discharge the cleaner by its own pressure.

5 Referring to Figure 6, the lower end of the sleeve 112 is threaded to a connector 119, which connector is substituted for the ordinary shoe of the bailer of the type shown in the above mentioned Omar A. Cavins patent, to convert that 10 tool into a cleaner of the type of the present application, the connector 119 carrying the pack-off shoe unit hereinafter described.

15 Fitted to the lower end of the connector 119 is a sleeve 121 forming a mandrel on which the packer elements are mounted, said mandrel having fixed therein adjacent its upper end a collar 122. An upper packer 124 and its thimble 130 is slid over the mandrel 121 until it engages a fixed collar 125 thereon. The packer and thimble are secured on the mandrel against collar 125 20 by a removable sleeve 126, the latter being secured by a bolt 128 onto the outside of the mandrel.

25 The lower packer 132 is held by a similar retaining sleeve 134 embracing the mandrel 121, this sleeve being retained in place by the bottom end guide 136 which is threaded into the lower end of the mandrel, the sleeve 134 being fixed to the mandrel by means of the retaining bolt 138.

30 In order to provide for free flow of fluid upwardly through the tool and past the packers, the lower packer retaining sleeve and the mandrel are provided with the aligned openings 140 below the lower packer, and the upper retaining sleeve and mandrel are provided with the aligned openings 142 above the upper packer, so that fluid may flow through the mandrel past the packers to permit lowering of the tool to the desired depth through the fluid in the well.

35 Secured within the collar 122 of the mandrel is an intake tube 144, which is closed at its lower end, the interior of this tube communicating with a passage through the connecting sub 119 which in turn connects with the suction chamber through the flapper valve 116 and the main valve 92. The tube 144 is secured in any suitable manner at one side of the mandrel, and at a point between the upper and lower packers, is provided with a plurality of ports 148 (Fig. 10) which are 40 in alignment with corresponding ports 150 in the wall of the mandrel between the packers. The interior of these aligned ports may be threaded for the reception of plugs 152, in order that any number of the ports may be closed to regulate 45 the total area of intake and velocity of flow of fluid into the cleaner. In place of plug closures, any sort of slide valve or similar arrangement may be provided to regulate the total inlet area of flow into the cleaner through the above mentioned side ports.

50 It will be apparent that the packers 124 may be removed for repair or replacement with facility, as the lower packer 132 with its retaining sleeve 134 may be conveniently removed from the mandrel by removing the bottom end guide 136, and similarly, the upper packer 124 with its retaining sleeve 126 may be removed from the mandrel by disconnecting the upper top sub connection 119.

55 70 Furthermore, if it is desired to operate with only one packer, either one of the packers 124 or 132 may be omitted. Particularly, the cleaner may be operated without the use of the upper packer 124 in a manner hereinafter described.

75 In operation, the tool is lowered into the well

suspended from the eye member 24 with the weight of the cleaner carried by the engagement of the hammer 20 with the anvil 12 as shown in Figure 2. During the lowering of the tool through the well, the up-trip unit and suction chamber assembly including the main valve 92 are in the condition shown in Figures 3 and 4, with the spring collar 40 and the springs 42 in their upper position, and with the valve 92 held upon its seat by the pressure of the spring 102, 10 the latching block 36 being retained within the bore of its housing 34, with the latching bolt in retracted position.

15 When the portion of the mandrel 121 between the packers is positioned at the desired level in the well for taking a charge, the lowering of the cleaner is stopped, and then it is moved upwardly. During this upward movement, the wall engaging springs 42 remain stationary by reason of their frictional engagement with the wall of 20 the well, and the valve operating rod 38 moves upwardly through the spring retaining sleeve 40, until the lower ends 52 of the springs engage the expanding collar 48, at which time the friction of engagement of the springs with the wall of the 25 well is increased by the expanding effect of the collar 48. This increased friction exerts a relatively downward force on the valve operating rod 38 during further elevation of the cleaner, which force is imparted to the latching block 36, which 30 in turn presses downwardly on the valve stem 54 which also acts as a valve operating rod to move the valve from its seat against the tension of the spring 102. The valve is latched in open position by the action of the bolt 58. 35

The opening of the valve results in an instantaneous rush of fluid from the well in through intake ports 148, 150, up through the tube 144, past the flapper valve 116 and into the suction chamber 65 past the main valve 92, this rush of 40 fluid being caused by the opening of the suction chamber 65, which, by reason of being air tight, is at atmospheric pressure before the main valve is opened. The rush of fluid carries the liquid and other materials from the well into the cleaner past the charge retaining or flapper valve 116. 45

50 Referring to Figure 6, it will be noted that the charge taking suction is confined to an area between the two packers, and thus the cleaning effect on the perforations in the well pipe will be more intense in this localized area. As will be apparent from Figure 6, fluid is drawn inwardly through the perforations in the well pipe between the packers, and due to the strength of the suction, well fluid is drawn from within the 55 interior of the pipe above the upper packer outwardly through the perforations in the pipe above said packer and down around the packer outside the perforated pipe, and inwardly through the perforations below the packer. Similarly, some fluid may be drawn from within the perforated pipe outwardly through the perforations below the lower packer and inwardly through the perforations above the lower packer. This flow of fluid thoroughly cleanses and opens up 60 the perforations.

65 If desired, the tool may be operated with the use of only a single packer. For instance, if it is desired in one operation to clean the well below a certain point, the lower packer may be omitted, 70 and the suction will then be taken inwardly through the perforations below the upper packer.

In the same manner, if it is desired to clean the perforations only above a certain point in the well, the upper packer may be omitted, and 75

then only the perforations above the lower packer will be cleaned, by suction, or by outward flow of fluid therethrough.

In this connection, when the upper packer is omitted, there may be a cleaning of the perforations by an outward flow of fluid under pressure therethrough. When such a tool is lowered into the well and stopped, the lower packer 132 forms in effect a false bottom, and when the valve leading to the suction chamber is opened by a subsequent upward movement of the tool, the rapid surge of fluid into the suction chamber substantially instantaneously removes a considerable volume of fluid from the well, and this causes a disturbance therein which results in a very rapid drop of the fluid above down into the well adjacent the area where the charge is taken. As the well fluid rushes downwardly, the cleaner becomes completely filled, and this downward rush of fluid is then suddenly arrested, and fluid is forced outwardly through the perforations in the well pipe at the point where the charge was taken, thus cleaning the same by an outward flow of fluid. Of course, there may be a continuing resurging of the fluid back and forth until a state of equilibrium is reached, but the dominant effect of the sudden removal of fluid with resulting unstable condition within the well, is the outward force of the fluid through the perforations adjacent where the charge was taken.

The cleaner may also be operated to clean the perforations in the well pipe above the packer 124 by an outward flow of fluid under pressure through the perforations, by jamming the sleeve 112 in such position with respect to the sleeve 108, that the port 120 is in alignment with the port 118. If it is desirable to operate the tool in this fashion, a plurality of pairs of ports 120 and 118 may be provided, instead of a single pair. With this arrangement, the tool is lowered to the desired point in the well with the port or ports 120 aligned with the port or ports 118, and when the tool is operated as hereinbefore described to effect an opening of the main valve 92, fluid is rapidly drawn into the tool through the ports 120 and 118 above the packer 124. This withdrawal of the fluid from the well causes a rapid drop in the fluid therein above the packer 124 and when the suction chamber of the cleaner becomes filled, this violent surging of fluid into the cleaner ceases, and a resulting reaction in the form of an outward flow of fluid through the perforations in the well pipe takes place. When the suction chamber 65 becomes filled, the path of least resistance for the surging fluid is outwardly through the perforations above the packer 124. Of course, there may be a resurging of fluid back and forth through the perforations in the well pipe until the fluid in the well reaches a state of equilibrium, but the dominant effect will be the outward flow of fluid through the perforations. It will be noted that when the cleaning is effected by the outward flow of fluid through the perforations, either when using the packer 124 or the packer 132 as the false bottom, there is no obstruction in the form of a seal between the outer wall of the cleaner and the inner wall of the well casing above this false bottom. Therefore, the downward flow of well fluid, when the cleaner is operated, is substantially unobstructed, so that the outward surging effect will be had when the flow of fluid into the cleaner ceases. The members 42 do not provide any substantial obstruction to this downward flow of fluid.

The cleaner of this invention may be operated

with only the combination of units A, B and C of Figure 1, and without the pack-off shoe unit D. When this is done, the lower end of the tool will be at the lower termination of the sleeve 112, or a shoe of the type shown in the above mentioned Cavins' Patent No. 2,088,151 may be utilized. When this tool is lowered into the well to the desired position, and then moved upwardly, the main valve is moved from its seat as previously described and a charge is taken into the tool through the bottom and side inlets and past the flapper valve 116. Removal of fluid from the well at any point will result in a pressure disturbance at that point, and when the rush of fluid into the tool suddenly ceases by reason of the filling of the suction chamber, there will be a reaction as previously described, which will tend to clean the perforations in the well pipe at the area where the fluid was removed, by an outward rush of fluid through said perforations. In operating the tool with the combination of the A, B and C units, the cleaning of the perforations will be more pronounced when the tool is resting on well bottom. When cleaning is done in this position, and fluid is suddenly removed from the well, and when the bailer suddenly becomes filled, the downward rush of fluid in the well toward the shoe of the cleaner is suddenly arrested, and by reason of the proximity of the well bottom, the path of least resistance for this fluid will then be outwardly through the perforations in the well pipe, to clean the same by an outward flow. As stated before, there will be a continuing resurging of the fluid back and forth through the perforations until equilibrium is established, but the dominant effect will be the cleaning by outward flow of fluid through the perforations.

If desired, the flapper valve 116 may be removed, and this cleansing of the perforations by an outward flow of fluid therethrough may be effected, without retaining the charge of fluid in the cleaner. That is, the tool may be utilized merely to create the pressure disturbance with resulting cleansing of the perforations, and any material which would have formed a part of the charge of the cleaner, to be removed from the well in the preferred manner of operation of the same, may be permitted to drop to the bottom of the well to be removed by subsequent bailing operations. In this manner of operation, only perforation cleaning will be performed, and no charge need be taken by the tool for removal from the well.

Furthermore, if it is desired to use the tool with the combination of A, B and C units, as shown in Figure 1, without the use of packers, to clean perforations in the well above the bottom of the same, a removable material, such as gravel and the like may be put into the well to form a false bottom above well bottom, and then the tool may be lowered onto the top of this quantity of gravel, and the valve opened, and the disturbance incident to the opening of the suction chamber valve will cause a cleaning of the perforations by an outward flow of fluid therethrough, the gravel tending to localize and intensify the outward flow of fluid to the area of the perforations above the quantity of gravel which has been placed in the well.

After such operations as described above, the gravel may be removed by ordinary bailing operations.

While the tool may be operated as described above without the use or operation of the charge retaining flapper valve 116, it is preferable to

use the tool with this valve functioning, in order to take the charge from the well subsequent to the cleaning operation.

It will be apparent that the cleaner of the present application may be moved upwardly and downwardly in the well as desired, to take a charge at any selected position. Furthermore, successive charges may be taken along the length of the perforated pipe in order to thoroughly clean all 10 of the perforations therein.

Various modifications of the cleaner disclosed herein may be made without departing from the scope of the invention.

I claim:

15. 1. In a cleaning device for wells, a casing, said casing having a port through which a charge is drawn into the same, a closed substantially air-tight chamber in said casing, said chamber having an inlet thereto, a valve for closing said inlet when the device is being lowered into the well, automatically operable means on said device for moving said valve from its seat when the device is lowered to the desired depth in the well, and then moved relatively to the wall thereof, to effect a rush of fluid into said casing through said port and through said inlet past said valve into said chamber, said means including a member positioned above said air-tight chamber for engaging the wall of the well and remaining in fixed relation thereto during said relative movement, and means for locking said valve in open position.
20. 2. In a cleaning device for wells, a casing, said casing having a port through which a charge is drawn into the same, a closed substantially air-tight chamber in said casing, said chamber having an inlet thereto, a valve for closing said inlet when the device is being lowered into the well, a spring for urging said valve to its seat, automatically operable means on said device for moving said valve from its seat when the device is lowered to the desired depth in the well, and then moved relatively to the wall thereof, to effect a rush of fluid into said casing through said port and through said inlet past said valve into said chamber to clean the perforations of the well pipe, said means including a member carried by said device above said chamber engaging the wall of the well and remaining in fixed relation thereto during said relative movement, and a packer mounted on the outside of said casing below said chamber to confine the cleaning to a particular area of perforations of the well pipe.
25. 3. In a cleaning device for wells, a casing, said casing having a port through which a charge is drawn into the same, a closed substantially air-tight chamber in said casing, said chamber having an inlet thereto, a valve for closing said inlet when the device is being lowered into the well, a spring for urging said valve to its seat, automatically operable means on said device for moving said valve from its seat when the device is lowered to the desired depth in the well, and then moved relatively to the wall thereof, to effect a rush of fluid into said casing through said port and through said inlet past said valve into said chamber to clean the perforations of the well pipe, said means including a member carried by said device above said chamber engaging the wall of the well and remaining in fixed relation thereto during said relative movement, and a packer mounted on the outside of said casing below said chamber to confine the cleaning to a particular area of perforations of the well pipe.
30. 4. In a cleaning device for wells, a casing, said casing having a port through which a charge is drawn into the same, a closed substantially air-tight chamber in said casing, said chamber having an inlet thereto, a valve for closing said inlet when the device is being lowered into the well, a spring for urging said valve to its seat, automatically operable means on said device for moving said valve from its seat when the device is lowered to the desired depth in the well, and then moved relatively to the wall thereof, to effect a rush of fluid into said casing through said port and through said inlet past said valve into said chamber to clean the perforations of the well pipe, said means including a member carried by said device above said chamber engaging the wall of the well and remaining in fixed relation thereto during said relative movement, and a pair of spaced packers mounted on the outside of said casing below said chamber on opposite sides of said port to confine the perforation cleaning operation to a particular area of the well pipe.
35. 5. In a device for cleaning the perforations of well pipe, a casing, said casing having a port through which a charge is drawn into the same, a closed substantially air-tight chamber in said casing, said chamber having an inlet thereto, a valve for closing said inlet when the device is being lowered into the well, automatically operable means on said device for moving said valve from its seat when the device is lowered to the desired depth in the well, and then moved relatively to the wall thereof, to effect a rush of fluid into said casing through said port and through said inlet past said valve into said chamber to clean the perforations of the well pipe, said means including a member carried by said device above said chamber engaging the wall of the well and remaining in fixed relation thereto during said relative movement, and a pair of spaced packers mounted on the outside of said casing below said chamber on opposite sides of said port to confine the perforation cleaning operation to a particular area of the well pipe.
40. 6. In a device for cleaning the perforations of well pipe, a casing, said casing having a port through which a charge is drawn into the same, a closed substantially air-tight chamber in said casing, said chamber having an inlet thereto, a valve for closing said inlet when the device is being lowered into the well, automatically operable means on said device for moving said valve from its seat when the device is lowered to the desired depth in the well, and then moved relatively to the wall thereof, to effect a rush of fluid into said casing through said port and through said inlet past said valve into said chamber to clean the perforations of the well pipe, said means including a member carried by said device above said chamber engaging the wall of the well and remaining in fixed relation thereto during said relative movement, and a pair of spaced packers mounted on the outside of said casing below said chamber on opposite sides of said port to confine the perforation cleaning operation to a particular area of the well pipe.
45. 7. In a cleaning device for wells, a casing, said casing having a port through which a charge is drawn into the same, a closed substantially air-tight chamber in said casing, said chamber having an inlet thereto, a valve for closing said inlet when the device is being lowered into the well, a spring for urging said valve to its seat, means for adjusting said spring to vary the pressure of said valve on its seat, and automatically operable means on said device for moving said valve from its seat when the device is lowered to the desired depth in the well and then moved relatively to the wall thereof, to effect a rush of fluid into said casing through said port and through said inlet past said valve into said chamber, said means

including a member positioned above said air-tight chamber for engaging the wall of the well and remaining in fixed relation thereto during said relative movement.

5. 8. In a cleaning tool for wells, a casing, a closed chamber in said casing, said chamber having an inlet thereto, a closure for said inlet, means for opening said inlet comprising an operating rod, an expansible element adapted to engage the wall of the well mounted for relative movement on said rod, means on said rod cooperating with said element to expand the same against the wall of the well and to thereby maintain said rod in fixed relation to said wall during a movement of said casing with respect thereto, said means on said rod being adapted to release said element from the wall of the well upon further movement of said casing with respect thereto, whereby said tool may be removed from the well with said element in released position.

20. 9. In a cleaning tool for wells, a casing, a closed chamber in said casing, said chamber having an inlet thereto, a closure for said inlet, means for opening said inlet comprising an operating rod, a member mounted for relative movement on said rod, an expansible bowed spring secured at one end to said member and having its other end free, said spring being adapted to engage the wall of the well intermediate its ends when expanded, a fixed knob on said rod adapted to engage the free end of said spring to expand the same against the wall of the well and to thereby maintain said rod in fixed relation to the wall of the well during a movement of said casing with respect thereto, said knob releasing said spring and thereby permitting it to contract from the wall of the well upon further movement of said casing, whereby said tool may be removed from the well with said spring in released position.

40. 10. In a cleaning tool for wells, a casing, a closed chamber in said casing, said chamber having an inlet thereto, a closure for said inlet, means for opening said inlet comprising an operating rod, a collar mounted for relative movement on said rod, a plurality of bowed springs, each of which is secured to one end of said collar and has its other end free, said other ends of said springs being bent outwardly, said springs being adapted to engage the wall of the well intermediate their ends when expanded, a fixed knob on said rod adapted to engage the outwardly bent ends of said springs to expand the same against the wall of the well and to thereby maintain said rod in fixed relation to said wall during a movement of said casing with respect thereto, the curved ends of said springs being adapted to ride over said knob permitting said springs to contract to release said springs from the wall of the well upon further

relative movement of said casing in the same direction with respect to the wall of the well, whereby said tool may be removed from the well with said springs in released position.

5. 11. In a tool for cleaning the perforations in well pipe by suction, a casing, a closed substantially airtight chamber in said casing, said chamber having an inlet thereto, a closure for sealing said inlet when the tool is being lowered into the well, means for opening said inlet when the tool is at the desired position in the well to draw a charge into said casing and thereby clean the perforations in the well pipe, comprising an operating rod, a wall drag element mounted for relative movement on said rod, a member fixed to said rod which actuates said wall drag element to force the same into tight engagement against the wall of the well and to thereby maintain said rod in fixed relation to the wall of the well during a relative movement of said casing with respect thereto, said member being adapted to release said wall drag element from tight engagement with the wall of the well after said inlet is opened upon further relative movement of said casing, whereby said tool may be removed from the well with said wall drag element in released position.

10. 12. In a device for cleaning perforations in a well pipe having a column of well fluid above the perforations, a casing including a closed substantially air-tight chamber having an inlet provided with a valve seat, a valve member for closing said inlet, means for maintaining said valve member on said seat to close said inlet when the cleaner is being lowered into the well pipe, a sealing member on said casing forming a seal with the interior of the well pipe below the perforations to be cleaned, said casing having an opening therein above said sealing member, said opening communicating with said inlet, and means for positively moving said valve member from its seat to open said inlet including a member engaging the interior of the well pipe and remaining in fixed relation thereto when said cleaner is moved upwardly in the well after having reached the desired depth therein, to cause a rapid flow of well fluid into said casing through said opening, said cleaner providing for substantially unobstructed downward flow of the column of well fluid around the same above said sealing member when said valve is moved from its seat, whereby the perforations in the well pipe above said sealing member and adjacent thereto are washed by an outward surge of fluid under pressure therethrough reacting from the termination of the rapid flow of fluid into said casing.

30. 35. 40. 45. 50. 55. PAUL CAVINS.
